TURBINE GOVERNING SYSTEM

Raymond Sheppard, Schenectady, N. Y., assignor
to General Electric Company, a corporation of
New York

Application April 23, 1946, Serial No. 664,266

14 Claims. (Cl. 137—158)

1

This invention relates to a governing system for a prime mover such as a turbine, particularly for a steam turbine adapted to drive a generator delivering electric energy to a network in parallel with a number of other similar turbo-generators. It is particularly adapted for governing such a turbine which is operated over long periods of time at a fixed speed and at an output which may be varied manually, as desired, but is ordinarily substantially constant.

An object of the invention is to provide a governing system for a turbine of the type described which will cause the turbine to operate at a fixed output and constant speed, yet which will react quickly in the event of either an increase or drop in speed relative to the established normal speed.

Another object is to provide a governing system for a turbine including a governor and means for adjusting the governor to select a desired load output, with means for overriding the adjusting means to limit the load to a preselected maximum.

A further object is to provide a turbine governing system having means for establishing a maximum load limit, with an under-speed release device for removing the limit when the turbine speed drops below a preselected value.

A still further object is to provide a turbine governing system of the type described in which the load limiting device can readily be adjusted during operation, either at the turbine or remotely from a control panel.

Another object is to provide a turbine governing system having a load limiting device with under-speed release means, which is insensitive to vibration and erratic action or "bobble" of the turbine speed governor, yet is extremely sensitive to changes in turbine speed.

Other objects and advantages will appear from the following description taken in connection with the accompanying drawings, in which Fig. 1 is a diagrammatic view, partly in section, showing one form which my improved governor system may take, and Fig. 2 is a performance chart illustrating some of the functions of which my system is capable.

As indicated above, governors embodying my invention are especially adapted for controlling a "fixed load turbine" driving a generator delivering electrical energy to a network in parallel with a number of other similar turbo-generators. In such networks it is customary to establish a common speed for all the turbo-generators by manually regulating the speed of one or a few

of the units. By thus manually controlling the speed of one turbo-generator, the speed of all the others is fixed at the desired value by the electrical characteristics of the network and the generators. This phenomenon, which makes it possible to establish a common speed for all the turbo-generators in a network by manually controlling the speed of one of them, is well known in the art; and the details of the electrical means and theory by which it is brought about are not necessary to an understanding of the present invention. It is sufficient to note that the turbine 1, in connection with which the present invention is described, is connected to a load device the speed of which is fixed by extraneous factors. A mechanical analogy would be the case where a plurality of turbines are directly geared by mechanical means at fixed speed ratios to drive a common output shaft, the speed of all the turbines being set to a desired value by manually adjusting the speed of one of them.

For service of the type described, the turbine 1 is required to operate for long periods of time at fixed speed and fixed load, that is, with the turbine control valve in a substantially fixed position. However, the turbine governor must be capable of immediately taking over control, either in the event of a rise in speed above the established value or in the event of a decrease in speed more than a predetermined amount below the established speed. The devices heretofore used in turbine governors to effect this function have been unsatisfactory because sensitive to vibration and to erratic movement of the speed governor known as "governor bobble." My invention provides a purely hydraulic-mechanical governing system which effectively performs the desired load limiting function, yet takes over quickly in the event of an abnormal deviation in speed.

Referring now to Fig. 1, my governing system is disclosed as applied to a steam turbine 1 driving a generator 2 which supplies electrical energy through a circuit breaker 3 to an electrical network 4. From the above discussion, it will be understood that the network 4 interconnects a plurality of similar turbo-generator units 1a, 2a which are caused to operate at a common speed established by means extraneous to the turbo-generator 1, 2, represented diagrammatically as being the manual speed-setting handwheel 1b of turbine 1a. Motive fluid is supplied to the turbine 1 through an inlet conduit 5 to the turbine inlet casing 6. The turbine inlet control valve means, represented diagrammatically by

the single valve 1, regulates the flow of motive fluid to the turbine inlet 8. It will be understood by those familiar with the turbine art that the pressure and temperature of the motive fluid supplied to chamber 6 are maintained substantially constant, while the throttling action produced by valve means 1 produces a variable pressure in chamber 8, the temperature in chamber 8 remaining substantially constant at the value obtaining in chamber 6. It will also be understood that with such an arrangement the output of or load on the turbine is a function of the position of valve means 7.

The valve 1 is positioned by a rod 9 connected to control rod 10 of a hydraulic servo-motor consisting of a turbine valve control piston 11 slidably arranged in a cylinder 12 formed in a housing 13. Piston 11 is biased downwardly in the valve-closing direction, by a spring 14 arranged in a chamber formed by cylinder 12 on the upper side of piston 11, which chamber is drained by means of a conduit 15. Governor operating fluid is admitted to chamber 12 to move piston 11 upward in the valve opening direction against the bias of spring 14, by pilot valve means described hereinafter.

A suitable speed responsive governor, shown at 16 in Fig. 1 as a conventional centrifugal fly-ball governor, is arranged to position a rotating pilot valve spindle 17 in a longitudinal direction as a function of the speed of turbine 1. It will be understood by those familiar with the art that other speed responsive devices, such as an electrical tachometer generator driven from the turbine shaft with solenoid means for positioning spindle 17 in accordance with the electrical signal from the tachometer generator, might also be used. Spindle 17 is provided with axially spaced cylindrical portions 18 and 19 slidably arranged in the longitudinal bore of a bushing 20. The bushing 20 is likewise slidably arranged in a bore 21 of housing 13, and has axially spaced ports 22 and 23 communicating with annular chambers 24 and 25, respectively, the latter being defined between the outer surface of bushing 20 and the wall of bore 21. The bushing 20 is also provided with a third set of ports 26 through which fluid may drain through the open lower end of bore 21.

Governor motive fluid is supplied from a suitable source past pilot valve means described hereinafter, through conduit 27 to the annular chamber 25 and the communicating ports 23. As clearly appears from Fig. 1 of the drawings, the cylindrical portion 19 of spindle 17 is arranged to control the flow of motive fluid from conduit 27 through chamber 25, ports 23, the annular space 28 defined between spindle 17 and the bore of bushing 20, thence through ports 22 to the annular chamber 24 and to conduit 29, which admits the motive fluid to the servo-motor cylinder 12. It will also be seen from the drawing that cylindrical portion 18 of spindle 17 is arranged to drain motive fluid from the servo-motor cylinder 12 through passages 29, 24, 22, and out the drain ports 26.

The lower end of bushing 20 is provided with a fork or yoke section 30 to which is connected a synchronizing and follow-up lever 31, by means of the pivot indicated in dotted lines at 32. It should be noted that spindle 17 passes freely through a central yoke portion 33 of lever 31. At one end lever 31 is connected by suitable links 34, 34a to the turbine valve actuating rod 10. This provides a follow-up connection between the servo-motor piston 11 and the pilot valve

spindle 17 in a manner which is well known in the art. The opposite end of lever 31 is connected to a fixed fulcrum 35, carried on a synchronizing screw 36, the position of which can be adjusted by means of a nut 37 arranged to be rotated by any suitable means, such as a gear 38 driven by a synchronizing motor in a manner which will be obvious from the drawing. It will be understood that the synchronizing motor is reversible and may be controlled (by suitable push-button means, not shown) from a remote station, for instance the control panel of the turbine 1. It will also be apparent that a suitable hand-wheel (not shown) may be provided on the shaft of the synchronizing motor so that the synchronizing screw 36 may be adjusted manually at the turbine. Screw 36 is provided with suitable stop means in the form of collars 39 and 40, which define the "no load" and "full load" settings, respectively.

The governor as described thus far is a conventional type which is well known in the art. The turbine 1 may be started and brought up to running speed by lowering synchronizing screw 36, causing bushing 20 to move downwardly, whereby motive fluid is admitted from conduit 27 through ports 23 past the cylindrical portion 19 to ports 22, thence through conduit 29 to the servo-motor cylinder 12. The pressure of the governor motive fluid in cylinder 12 causes piston 11 to rise against the bias of spring 14 and open turbine control valve 7. The upward movement of piston rod 10 causes the follow-up links 34, 34a to move lever 31 so as to raise bushing 20 and cause cylindrical spindle portion 19 to interrupt the flow of motive fluid through ports 23, thus halting the upward movement of piston 11. When synchronizing screw 36 is moved upwardly toward the no load position, bushing 20 also moves upwardly so that the cylindrical portion 18 uncovers drain ports 26, permitting motive fluid in the servo-motor cylinder 12 to be drained therefrom.

For a given setting of synchronizing screw 36, the speed governor 16 will maintain a corresponding fixed position of piston 11, in the following manner. If the speed of turbine 1 increases slightly, the speed governor flyweights move outwardly thus drawing spindle 17 downward, causing cylinder 18 to uncover ports 26 to drain cylinder 12. This permits piston 11 to descend slightly until the follow-up linkage 34, 34a restores bushing 20 to a position in which cylinder 18 again blocks the drain ports 26. If turbine speed should decrease slightly, the speed governor flyweights move inwardly causing spindle 17 to move upwardly, whereby the cylinder 18 uncovers the ports 23, admitting motive fluid from conduit 27 to servo-motor cylinder 12. This causes piston 11 to rise until the follow-up linkage restores bushing 20 to the aligned position shown in Fig. 1, in which cylinder 18 just blocks ports 23.

My invention adds to the conventional governing means described above additional means for limiting the upward movement of the turbine valve control piston 11. This means consists of a second pilot valve arrangement indicated generally at 41 in Fig. 1. This second pilot valve means comprises a bushing 42 connected to piston 11 and slidably arranged in bore 43 in housing 13. Bushing 42 is provided with one or more ports 44 through which governor motive fluid is admitted from a suitable source (not shown) through conduit 45 to the interior of bushing 42. The bushing is also provided with a second

set of ports 46 through which governor motive fluid is admitted to conduit 27, as will be clear from Fig. 1. Slidably arranged in the bore of bushing 42 is a second pilot valve 47 having cylindrical portions 48 and 49 respectively. It will be apparent that spindle 47 and cylinder 48 form with the bore of bushing 42 and annular chamber to which fluid is supplied through ports 44, and from which cylinder 49 permits motive fluid to flow through ports 46 to conduit 27. Hereinafter this second pilot valve will be referred to as the "load limit pilot," since its function is to establish a limiting position beyond which the governor cannot cause piston 11 to move, in valve-opening direction.

A plurality of devices are provided for positioning the load limit pilot 47. The first means consists of an adjustable stop in the form of a bellcrank supported on a fixed pivot 50 and having a first arm 51 arranged to engage a stop member 52 secured to a rod 53, which is connected to the pilot valve 47. The extreme end of rod 53 is provided with a flange 54 and a coil spring 55 arranged between flange 54 and the upper surface of bellcrank arm 51. This arrangement permits rod 53 to move downwardly, regardless of the position of the adjustable stop 51, while the upward movement of rod 53 is positively limited by the engagement of member 52 with the stop lever 51. The stop member 51 is positioned by means of an arm 56 which is pivotally connected to the end of an adjusting screw 57. Screw 57 is arranged to be freely slidably in a support housing 58, which carries at the left end of screw 57 a rotatable bushing 59 adapted to be turned manually by a hand-wheel 60. Radially extending keys or splines 61 secured to screw 57 are arranged to slide longitudinally in suitable keyways in the bore of bushing 59.

Screw 57 carries a nut 62 which does not rotate but travels longitudinally on screw 57 as the latter is turned. The position of nut 62 is ordinarily fixed by mechanical latching means including links 63, 64, the latter of which is arranged to be engaged by a latch member 65. Latch member 65 has an end portion engaged by a tripping rod 66, and a second cam-shaped end 67 arranged to be engaged by the nut 62 for resetting latch 65, as described below. Nut 62 is biased to the right by means of a coil spring 68 arranged between the end of the nut and the adjacent end of bushing 59. Movement of screw 57 to the right is limited by the movement of a collar 69 to the dotted line position shown at 69a in Fig. 1.

With nut 62 held fixed by the linkage 63, 64 and the latch 65, it will be apparent that screw 57 may be adjusted longitudinally by rotating hand-wheel 60, so that the bellcrank 51, 56 may be positioned anywhere from the "no load position," indicated by dot-dash lines 70 to the "full load position," indicated by the dot-dash lines 71.

The emergency over-speed governor, indicated diagrammatically at 72 in Fig. 1, is driven from the turbine shaft and is arranged to engage a latch lever 73 when turbine speed reaches the value for which the emergency governor is set. It will be understood by those skilled in the art that this emergency governor is a slightly unbalanced centrifugal device which moves to an eccentric position under emergency over-speed conditions, as indicated by the dotted circle 74 in Fig. 1. Such movement causes latch

73 to move counterclockwise, thus releasing spindle 75 which is then biased downwardly by a coil spring 76 so as to move trip rod 66 downwardly to unlatch member 65 from the link 64. When link 64 is thus freed, biasing spring 68 causes the nut 62 to move to the right, the keys 61 sliding freely in the bushing 59 until collar 69 reaches its limiting position 69a, with link 64 in the dot-dash position 64a. This movement of screw 57 causes bell-crank 51, 56 to move to the "no load" position 70, and this in turn causes the rod 53 to be moved downwardly. The action of the load limit pilot 47 will now be noted. It will be apparent that as the pilot valve 47 moves downwardly from the position shown in Fig. 1, cylinder 49 progressively blocks the ports 46 until finally the supply of motive fluid from conduit 45 to conduit 27 is interrupted altogether. When this happens, the speed governor 16 and the first pilot valve 17 are no longer capable of moving piston 11 in the valve-opening position. The manner in which pilot valve 47 acts to limit the upward movement of piston 11 will now be apparent. As piston 11 moves upwardly, for instance under the control of governor 16 and synchronizing screw 36, bushing 42 likewise moves, until the ports 46 are entirely blocked by cylinder 49. The upward movement of piston 11 is therefore stopped, because cylinder 49 interrupts the flow of motive fluid to the first pilot valve 17. As will be understood by those skilled in the art, there is an appreciable amount of leakage between the respective cylinder members 18, 19, bushing 20, and the bore 21. By reason of this leakage, biasing spring 14 will cause piston 11 to start downwardly as soon as cylinder 49 interrupts the supply of motive fluid to conduit 27 and the first pilot valve. This downward creepage of piston 11 causes the ports 46 in bushing 42 to be slightly uncovered by cylinder 49 whereby motive fluid is again supplied through conduit 27 to the first pilot valve, which may then admit motive fluid to the chamber 12 to restore piston 11 to the position in which cylinder 49 is just aligned with the ports 46. It will therefore be seen that the load limit pilot 47 establishes a limiting position beyond which governor 16 cannot cause piston 11 to move in the valve-opening direction.

Control rod 53 may be moved downwardly, either by actuating hand-wheel 60 to move stop 51 toward the "no load position" 70, or by reason of disengagement of the latch means 64, 65 under the influence of emergency speed governor 72. Such downward movement of rod 53 and the pilot 47 promptly causes cylinder 49 to block the passages 46, shutting off the supply of motive fluid to the first pilot valve as noted above, whereupon piston 11 creeps downwardly by reason of the leakage mentioned above. If the downward movement of rod 53 continues, the downward creepage of piston 11 will not cause cylinder 49 to uncover ports 46, and therefore the downward creepage continues. The result is that when pilot 47 moves downwardly, piston 11 is caused to accompany it. When stop member 51 moves all the way to the "no load position" 70, pilot 47 causes piston 11 to move to its lowermost position, in which valve 7 is entirely closed.

In accordance with my invention, a second device is provided for positioning control rod 53. This consists of a second bellcrank supported on a fixed pivot 77 and having a first arm 78 arranged to engage the upper surface of flange 54,

and a second arm 79 connected to the end of a longitudinally movable screw 80. Screw 80 is arranged to slide longitudinally in a support housing 81, and is arranged to be rotated in either direction by means of a bushing 82 having internal keyways or splines engaging keys 83 on the right-hand end of screw 80. Bushing 82 may be rotated manually, at the turbine, by means of a hand-wheel 84. It may also be remotely adjusted, from the turbine control panel, by means of the load limit motor 85 which has suitable circuits with push-button control (not shown). As will be apparent from Fig. 1, the motor 85 is geared to bushing 82 by means of a friction coupling including a friction disk 86 biased against the side of gear 87 by a suitable coil spring 88. This arrangement permits screw 80 to be rotated by hand-wheel 84, with the friction coupling slipping and gear 87 remaining stationary.

Carried on the screw 80 is a nut 89 arranged to normally be held fixed by latch means including links 90 and 91, the latter of which is adapted to be engaged by a latch 92. Member 92 has a projecting tripping arm 93 engaged by coil spring 93a which biases latch 92 into latching engagement with link 91, and also causes the tripping arm 93 to remain engaged with the projecting end of piston rod 94 of a hydraulic servo-motor 95, the function of which will be seen hereinafter.

It will be apparent from Fig. 1 that as long as latch 92 holds nut 89 fixed, the screw 80 can be adjusted longitudinally by proper rotation of screw 80, either by hand-wheel 84 or the load limit motor 85. It will also be apparent that such longitudinal movement of screw 80 will cause bellcrank 78, 79 to be appropriately positioned between the "full load position," shown in full lines in Fig. 1, and the "no load position" indicated by the dot-dash lines 96. As screw 80 is retracted by its rotation in nut 89 from the position represented in Fig. 1, arm 78 of the bellcrank lever will descend until it engages flange 54. Further movement of screw 80 to the right will cause arm 78 to move rod 53 downwardly, stop member 52 meanwhile moving downwardly away from the primary stop lever 51. It will be seen that screw 80 and the devices associated with it constitute secondary means for positioning rod 53 in the range below the upper limiting position established by the engagement of member 52 with stop lever 51. Thus the maximum position to which piston 11 can be moved in valve-opening direction by speed governor 16 and the synchronizing screw 36 may be limited by the screw 57 acting independently of screw 80, or by the screw 80 acting to position rod 53 in the range below the limiting position established by the stop lever 51. In other words, screw 57 and its associated devices constitute means for establishing a primary or absolute maximum limit beyond which piston 11 cannot be moved in the valve-opening direction. On the other hand, screw 80 and its associated devices constitute means for establishing a secondary limit, within the range below the absolute limit established by screw 57.

Associated with the screw 80 are under-speed release means arranged to render ineffective the secondary load limiting device when the turbine speed decreases below a preselected value. This under-speed release mechanism comprises the servo-motor 95, including a piston 97 longitudinally slidable in a cylinder formed in the housing 81. Piston 97 is biased to the left by a coil spring 97a and is adapted to be moved to the right by fluid pressure communicated to piston 97 through

conduit 98. It will be apparent from Fig. 1 that movement of piston 97 causes the piston rod 94 to engage trip arm 93 so as to disengage latch 92 from link 91, permitting coil spring 99 to bias nut 89 and screw 80 to the left, link 91 thereby being moved to the dot-dash position 91a. Engagement of the collar 100 with housing 81, as shown in Fig. 1, determines the extreme position or "full load" position of the screw 80.

In order to reset the secondary load limit device so that nut 89 is again secured by latch 92, the procedure is as follows. Screw 80 is rotated so that nut 89 moves to the right, collar 100 still engaging housing 81. As nut 89 moves to the right, the end of link 91 rides up the inclined cam edge 101 of latch 92, thus causing the latch to be rotated counterclockwise against the bias of spring 93a, until the end of link 91 snaps into the position shown in Fig. 1. Spring 94 will then cause latch 92 to secure link 91 until tripped by action of servo-motor 95.

The supply of motive fluid through conduit 98 to servo-motor 95 is controlled by a third pilot valve indicated generally at 102 in Fig. 1. This under-speed release pilot is arranged to be positioned by the turbine speed governor 16, and may be conveniently associated directly with the first pilot 17. As shown in Fig. 1, the underspeed release pilot 102 includes a spindle 103 formed as a continuation of the first pilot spindle 17 and having a cylindrical portion 104. The pilot 103, 104 is slidably arranged in a bore 105 formed in a bushing 106 which is separate from bushing 20 and axially adjustable in the bore 21 by means of a thread engaged by an adjusting nut 107, which may be secured to housing 13 by one or more suitable threaded fastenings 108. It will be apparent that the position of bushing 106 may be adjusted longitudinally relative to bore 21 by removing the threaded fastening 108, rotating nut 107 to a desired position, and reassembling the fastening 108.

The bushing 106 is provided with a first set of ports 109 arranged to receive motive fluid from conduit 45 by way of the annular space 110 and conduit 111 formed in housing 13. The chamber defined by bore 105 above cylinder 104 is drained by means of a passage 112 in bushing 106. It will be apparent from Fig. 1 that fluid collecting in the upper portion of bore 21, above bushing 20, will be drained through the passage 113. It will also be seen that the upper end of spindle 17 forms an annular shoulder 114 arranged to cooperate with the adjacent end of bore 105. When shoulder 114 is in the position shown in Fig. 1, forming a clearance space 115 with the adjacent end of bushing 106, servo-motor 95 is drained of fluid through conduit 98, the annular space 116 surrounding pilot rod 103, and the clearance space 115.

The position of the first pilot 17, 18, 19 shown in Fig. 1 represents the condition when the speed is normal and the speed governor 16 and synchronizing screw 36 are in control of the speed and load. If now the speed should drop below the established speed, then spindle 17 will rise until finally shoulder 114 closes completely the clearance space 115, and simultaneously cylinder 104 uncovers port 109, whereupon motive fluid from conduit 45 will flow through conduit 111, port 109, the annular space 116, thence to conduit 98 and servo-motor 95. Piston 96 is thereby moved to the right against the bias of spring 97a, causing latch 92 to disengage

link 91, with the result that nut 89 and screw 88 are biased quickly to the "full load" position by spring 99. It will be apparent that the size of the clearance space 115 determines the amount the turbine speed must drop below the established speed before servo-motor 95 is actuated. It will also be apparent from Fig. 1 that this critical speed drop required to actuate servo-motor 95 can be adjusted by properly positioning bushing 106 by means of the adjusting nut 107.

The functions which my improved turbine governing system is capable of performing will be seen from the following examples. The operation of the system will be described in connection with the performance curves of Fig. 2, in which the abscissa represents the turbine load or output, in per cent of rated load, while the ordinate represents turbine speed, expressed in per cent of rated speed.

With the primary load limit screw 57 retracted and the secondary load limit screw 89 extended to their respective "full load" positions, it is possible to open valve 7 and bring turbine 1 up to the normal speed by means of the synchronizing screw 36 and the operation of the speed governor 16, in the manner used with conventional turbine governors. This is accomplished simply by rotating screw 36 from the "no load" position to a desired setting corresponding to the load and speed desired. During such operation, the load limit pilot valve 47 is in its uppermost or "full load" position and operating fluid from conduit 45 is permitted to pass to the speed control pilot 17 without interference from the load limit pilot.

Alternately, the turbine may be started and brought up to speed by means of the primary load limit screw 57. In order to accomplish this the latch 64, 65 must be reset, if the turbine was previously stopped by tripping action of the emergency over-speed governor 74. This resetting operation is accomplished by rotating hand-wheel 60, collar 69 being in its dotted line position 69a, so as to move nut 62 to the left, link 64 moving from the dot-dash position 64a toward the position shown in full lines. Movement of nut 62 is continued until it engages the end portion 67 of latch member 65. Further movement of nut 62 against the end portion 67 will cause latch 65 to rotate counterclockwise so as to engage the end of link 64. Counterclockwise movement of latch 65 will of course raise tripping rod 66 against the bias of spring 76 and cause lever 73 to drop counterclockwise so as to engage the end portion 75 of rod 68. The overspeed emergency trip is thereby reset to the position shown in full lines in Fig. 1. Hand-wheel 60 can then be rotated to retract screw 57 to the left, collar 69 being thereby drawn from its dotted line position 69a and bellcrank 51, 56 being rotated counterclockwise so as to raise control rod 53. This motion causes piston 11 to follow the pilot 47 upwardly, by reason of the supply of governor motive fluid from conduit 45 past pilot 47 through the speed control pilot 17, 18, 19 to cylinder 12. When piston 11 rises to a position corresponding to the turbine load for which synchronizing screw 36 is set, pilot 17 will bring cylinders 18, 19 into aligned position with ports 26, 23 respectively, as shown in Fig. 1, whereupon the speed governor 16 takes over control and prevents a further rise of piston 11. Further upward motion of rod 53 merely raises

pilot 47 so as to provide free communication between conduits 45 and 27. With the turbine thus brought to the desired speed and load, determined by the position of synchronizing screw 36, the generator 2 is connected to the network 4, as by closing circuit breaker 3. Thereafter the speed of turbo-generator 1, 2 will be established by reason of its interconnection with the other turbo-generators connected to network 4, as described above.

Assuming that the synchronizing screw 36 was set to its "half load" position, substantially that represented in Fig. 1, then the speed governor 16 will tend to control the turbine in accordance with the curve *an* in Fig. 2. This curve will be recognized by those skilled in the art as the "speed regulation curve," representing the change in speed of the turbine from "full load" to "no load" when controlled by the speed governor 16. 15 However, since the speed of turbine 1 is being held fixed (at 100 per cent of rated speed) by reason of its interconnection with the turbo-generator 1a, 2a, the governor 16 will always rotate at this established speed, and the action 20 of the governor will be to hold the turbine load fixed at the point *p* in Fig. 2. It will be seen that the point *p* corresponds to 100 per cent speed (fixed by the interconnection of turbo-generator 1, 2 with unit 1a, 2a in the network 4) and 50 25 per cent load (determined by the "half load" setting of synchronizing screw 36). If the synchronizing screw 36 were set to its "full load" position, then the governor would try to follow the curve *xy*, but would be limited to operation 30 at the point *y* by reason of the interconnection with other turbo-generators, point *y* representing 100 per cent load at 100 per cent of the established speed.

Now, assuming that synchronizing screw 36 is 35 set at "half load" so that the governor will tend to follow curve *an* as described above, the primary load limit screw 57 may be moved to the right so as to rotate bellcrank 51, 56 clockwise and lower pilot 47. When pilot 47 gets to its 40 "half load" position, cylinder 49 will be just aligned with the ports 46. In this condition, neither the synchronizing screw 36 nor the governor 16 can cause piston 11 to move above its "half load" position. If now rod 53 is lowered 45 still further so that pilot 47 goes below the "half load" position, then piston 11 will follow pilot 47 downwardly, as described above. Conversely as pilot 47 rises, piston 11 will follow it upwardly until, when the "half load" position is reached, 50 cylinder 49 again becomes just aligned with ports 46. When pilot 47 moves above this "half load" 55 position, ports 46 are no longer blocked by cylinder 49 and pilot 17 takes over control in accordance with the operation of governor 16.

60 Assume now that the primary load limit screw 57 is set by means of hand-wheel 60 to the position corresponding to "three-fourths load," approximately that shown in full lines in Fig. 1. Governor 16 will now control pilot 17 to position 65 piston 11 in accordance with the setting of synchronizing screw 36. The primary load limiting device now serves only to establish "three-fourths load" as the absolute limit above which synchronizing screw 36 will be ineffective to position piston 11. Thus it will be seen that the primary limiting screw 57 provides means for setting manually, at the turbine by means of hand-wheel 60, a limiting load which may not be exceeded by controlling synchronizing screw 70 75 36 remotely from the turbine control panel.

11

Thus, a remote operator at the turbine control panel is prevented from inadvertently adjusting screw 36 to call for a load above the preselected desired maximum. Setting the primary load limit device to a position corresponding to "three-fourths load" has the effect of establishing the line *cd* in Fig. 2 as an upper limit, so that governor 16 and synchronizing screw 36 are able to exercise control only in the area to the left of line *cd*.

Now with synchronizing screw 36 set at "half load" and the primary load limit screw 57 set at "three-fourths load," the secondary load limit screw 80 may be adjusted. It is first necessary to adjust bushing 106 so that the clearance 115 corresponds appropriately to the maximum speed drop to be permitted. It may be assumed that the under-speed release pilot 102 is adjusted so that servo-motor 95 will be actuated if the turbine speed decreases one per cent, that is, to 99 per cent of the established value. The effect of thus adjusting the under-speed release pilot 102 is to establish the line *ti* in Fig. 2 as the minimum value below which turbine speed will not fall.

Now, assuming that latch 91, 92 has been reset to the position indicated in Fig. 1, by the method described above, the secondary load limit screw 80 can be adjusted, by means of hand-wheel 84 at the turbine or remotely from the control panel by means of load limit motor 85. As screw 80 is retracted from the position shown in Fig. 1, bellcrank 78, 79 rotates counterclockwise until the arm 78 just engages collar 54 when screw 80 is set to the "three-fourths load" position (the limiting value established by screw 57). If now screw 80 is moved below the "three-fourths" position, then rod 53 is moved downwardly by the engagement of lever 78 with collar 54, with the result that stop member 52 moves away from the primary stop lever 51. The secondary load limiting screw 80 now determines the maximum load beyond which piston 11 cannot rise. If screw 80 is set to the "half load" position, then cylinder 49 of the load limit pilot 47 again becomes aligned with ports 46, and upon further retraction of screw 80 causing downward movement of pilot 47 below this point screw 80 takes control of the system away from governor 16 and the synchronizing screw 36 (which is calling for "half load" operation).

Assume now that the secondary load limit screw 80 is set to the "20 per cent load" position. This has the effect of establishing the line *sf* in Fig. 2 as the limit above which the turbine may not operate. In this condition, the synchronizing screw 36 (set at "half load" position) prevents operation above the line *ar* in Fig. 2; and the secondary load limit screw 80 restricts operation to the left of the line *sf*. If now, due to some abnormal operating condition such as a disturbance somewhere in the network 4, the normal speed which is established for the entire network varies so that the speed of turbine 1 drops from 100 per cent to 99½ per cent (from point *k* to *g* in Fig. 2), the speed governor 16 will raise the pilot 17 in an attempt to admit motive fluid to cylinder 12 and raise piston 11 so as to open valve 7 and restore the speed to 100 per cent. However, this action is prevented because the cylinder 49 of pilot 47 blocks ports 46 to interrupt the flow of motive fluid through conduit 27 to the pilot 17, 18, 19. If now the speed drops still further, for instance to 99 per cent represented by point *h* in Fig. 2, then governor 16 raises pilot 17 and the under-speed release pilot

12

103 sufficiently that cylinder 104 permits fluid to flow from conduit 111 into conduit 98 to actuate servomotor 95. Latch 91, 92 is hereby disengaged and spring 99 moves nut 89 and screw 80 to the extreme left or "full load" position shown in Fig. 1. This has the effect of removing the limiting line *sf* in Fig. 2. Upward movement of the lever 78 permits rod 53 to rise until member 52 engages stop lever 51. Thus pilot 47 is restored to the "three-fourths load" position, so that the line *cd* in Fig. 2 again becomes the limit above which the turbine will not operate. However, piston 11 will follow pilot 47 upwardly only until it reaches the "half load" position. This increase in load is represented by the line *hm* in Fig. 2. At point *m*, which is approximately at 72 per cent rated load, the speed governor 16 resumes control since the synchronizing screw 36 is set to call for operation along the line *an*. Thus it will be seen that as long as the speed established in the network is at the subnormal value of 99 per cent, turbine 1 will operate at 72 per cent of its rated load, although synchronizing screw 36 is set to call for "half load" (at 100 per cent rated speed). If now the established speed in the network rises to 100 per cent of the normal value, then governor 16 will cause the turbine operation to follow the line from *m* to *p* along the half load curve *an*.

Now if, with synchronizing screws 36 set at "half load," the primary load limit screw 57 set at "three-fourths load," and the secondary load limit screw 80 set at "20 per cent" as before, the established speed in the network 4 should suddenly drop to 98 per cent of the normal value, the operation of turbine 1 would follow the line from *k* to *s* in Fig. 2. When the point *h* is reached, the under-speed release pilot 102 will energize servo-motor 95 as before and trip the secondary limit screw 80 to its "full load" position. Pilot 47 is thus permitted to rise to the "three-fourths load" position determined by lever 51, the turbine operation following the line *s* to *c* in Fig. 2. It should be noted that without the primary limit 51 set at "three-fourths load" so as to establish the line *cd* as an upper limit, the load on turbine 1 would have increased along the curve *sc* and to the point *n* on the half load curve *an*. Since point *n* represents 92 per cent of rated load, it may be undesirable to cause the load on turbine 1 to suddenly increase to such a high value. Therefore, the primary load limit screw 57 serves to prevent the load rising above the predetermined maximum. If now the established network speed rises, the operation of turbine 1 will follow the line *c* to *b*. At point *b* the governor 16 takes over and the operation of the turbine will follow the line *bmp*, as dictated by the "half load" setting of synchronizing screw 36.

It will be seen from the above that with the synchronizing screw 36, primary load limit screw 57, and secondary load limit screw 80 adjusted as described above, the area defined by the lines *arht* in Fig. 2 represents the zone in which the turbine can operate without causing any components of the governing system to act. If operation tends to pass into the area above line *ar*, then governor 16 will lower piston 11 so that operation returns to the line *ar*. The secondary load limit screw 80 establishes the upper limit line *rh*; and if the operation drops below the line *th*, then the under-speed release mechanism acts to remove the line *sf* as the upper limit and

13

frees the turbine to operate anywhere within the area *arpmht*.

It will be apparent that it is not necessary to use the primary load limit screw 57 to establish the limit *cd*. Bellcrank 51, 56 may be left in its "full load" position so that control will be effected by the secondary load limit screw 80 and the governor 16, as set by the synchronizing screw 36. The primary load limit screw 57 will act only in starting up or shutting down the turbine by means of hand-wheel 60, or in the event that emergency speed governor 72 trips the latch 64, 65. Furthermore, instead of being positioned only by the hand-wheel 60, the primary stop 51 may be arranged to be positioned automatically by other means responsive to some operating condition of the powerplant, for instance the boiler pressure.

From the above examples it will be seen that my invention provides an improved turbine governing system having a plurality of load limiting devices, one of which establishes a primary limiting load which may not be exceeded and another which establishes a secondary limit below the primary limit, with under-speed release mechanism for removing the secondary limit in the event that the turbine speed drops more than a preselected amount.

What I claim as new and desire to secure by Letters Patent of the United States is:

1. In a governing system for a prime mover powerplant having inlet valve means, the combination of a source of governor operating fluid under pressure, motor means for regulating the inlet valve means including a cylinder with a piston for positioning said valve means and first pilot valve means for controlling the flow of operating fluid from said source to the cylinder, governor means responsive to prime mover speed for positioning the first pilot valve, first adjustable means for limiting movement of the piston in valve-opening direction to a first preselected value, second adjustable means for limiting movement of the piston in valve-opening direction to a second preselected value smaller than said first limiting value, and under-speed release means associated with the speed governor for rendering ineffective said second adjustable means to restore control of the system to the speed governor as limited by the first adjustable means when the speed decreases from normal to a preselected minimum value.

2. In a governing system for a prime mover powerplant unit having inlet valve means, the combination of a source of governor operating fluid under pressure, motor means for regulating the inlet valve including a cylinder with a piston for positioning said valve and first pilot valve means for controlling the flow of operating fluid from said source to the cylinder, governor means responsive to prime mover speed for positioning the first pilot valve, means for limiting movement of the piston in valve-opening direction to a preselected position comprising second pilot valve means associated with the piston and arranged to interrupt the flow of operating fluid to the first pilot valve when the piston reaches said preselected limiting position, adjustable means for positioning the second pilot valve to select said limiting position, and under-speed release means associated with the speed governor for rendering ineffective the adjustable means to restore control of the system to the speed governor when the speed decreases from normal to a preselected minimum value.

14

3. In a governing system for a prime mover powerplant unit having inlet valve means, the combination of a source of governor operating fluid under pressure, motor means for regulating the inlet valve means including a cylinder with a piston for positioning said valve means and first pilot valve means for controlling the flow of operating fluid from said source to the cylinder, governor means responsive to prime mover speed for positioning the first pilot valve, means for limiting movement of the piston in valve-opening direction to a plurality of preselected positions comprising second pilot valve means associated with the piston and arranged to interrupt the flow of operating fluid to the first pilot valve when the piston reaches said preselected limiting position, first adjustable stop means for limiting movement of the second pilot valve to a first preselected position, second adjustable means for moving the second pilot valve to any position within the range of movement below the limiting position established by said first stop means, and under-speed release means associated with the speed governor for rendering ineffective said second adjustable means to restore the system to control by the speed governor as limited by said first adjustable stop means when the speed decreases from normal to a preselected minimum value.

4. In a governing system for a prime mover powerplant unit having inlet valve means, the combination of a source of governor operating fluid under pressure, motor means for regulating the inlet valve including a cylinder with a piston for positioning said valve and first pilot valve means for controlling the flow of operating fluid from said source to the cylinder, governor means responsive to prime mover speed for positioning the first pilot valve, means for limiting movement of the piston in valve-opening direction to a plurality of preselected positions comprising second pilot valve means associated with the piston and arranged to interrupt the flow of operating fluid to the first pilot valve when the piston reaches said preselected limiting position, first adjustable stop means for limiting movement of the second pilot valve to a first preselected position, second adjustable means for moving the second pilot valve to any position within the range of movement below the limiting position established by said first stop means, and under-speed release means including a servo-motor for rendering ineffective said second adjustable means to restore the system to control by the speed governor as limited by the first adjustable stop means, and third pilot valve means positioned by the speed governor for controlling said operating fluid to actuate said servo-motor when the speed decreases from normal to a preselected minimum value.

5. In a governing system for a prime mover powerplant unit having inlet valve means, the combination of a source of governor operating fluid under pressure, motor means for regulating the inlet valve means including a cylinder with a piston for positioning said valve means and a pilot valve for controlling the flow of fluid from said source to the cylinder, governor means responsive to prime mover speed for positioning the pilot valve, means for limiting the movement of the piston in valve-opening direction to a desired maximum value, and under-speed release means associated with the speed governor for rendering ineffective said limit means when the

15

speed decreases from normal to a preselected minimum value.

6. In a governing system for a prime mover powerplant unit having inlet valve means, the combination of a source of governor operating fluid under pressure, motor means for regulating the inlet valve including a cylinder with a piston for positioning said valve and pilot valve means for controlling the flow of fluid from said source to the cylinder, governor means responsive to prime mover speed for positioning the pilot valve, adjustable means for limiting the movement of the piston in valve-opening direction to a desired maximum value, said adjustable means including second pilot valve means associated with the piston and arranged to stop the flow of operating fluid from the source to the first-mentioned pilot valve when the piston moves to said limiting position, and under-speed release means associated with the speed governor for rendering ineffective said adjustable means when the speed decreases from normal to a preselected minimum value.

7. In a governing system for a prime mover powerplant unit having inlet valve means, the combination of a source of governor operating fluid under pressure, motor means for regulating the inlet valve including a cylinder with a piston for positioning said valve and pilot valve means for controlling the flow of fluid from said source to the cylinder, governor means responsive to prime mover speed for positioning the pilot valve, adjustable means for limiting the movement of the piston in valve-opening direction to a desired maximum value, said adjustable means including second pilot valve means associated with the piston and arranged to stop the flow of operating fluid from the source to the first mentioned pilot valve when the piston moves to said limiting position, and under-speed release means for rendering ineffective said adjustable means, including a servo-motor with third pilot valve means positioned by the speed governor and arranged to control the flow of said operating fluid to actuate the servo-motor when the speed decreases from normal to a preselected minimum value.

8. In a governing system for a prime mover powerplant unit having inlet valve means and adapted to operate at a preselected normal speed, the combination of a control member for regulating the inlet valve means, governing means adapted to control the position of the control member to maintain prime mover speed at the preselected normal value, synchronizing means for adjusting the governing means to change the normal position of the control member, adjustable stop means for preventing movement of the control member in valve-opening direction beyond a preselected limiting position, and under-speed release means controlled by the governing means for rendering ineffective said stop means whereby the system is restored to unrestricted control by the speed governor when the speed decreases below the normal speed to a preselected minimum value.

9. In a governing system for a prime mover powerplant unit having inlet valve means and adapted to operate at a preselected normal speed, the combination of a control member for regulating the inlet valve means, governing means adapted to control the position of the control member to maintain prime mover speed at the preselected normal value, synchronizing means for adjusting the governing means to change the normal position of the control member, adjustable stop means for preventing movement of the control member

16

in valve-opening direction beyond a preselected limiting position, and under-speed release means including a servo-motor for rendering ineffective said stop means, and pilot means associated with the governing means for controlling the flow of said operating fluid to actuate said servo-motor when the speed decreases below the normal speed to a preselected minimum value whereby the system is restored to unrestricted control by the governing and synchronizing means.

10. In a governing system for a prime mover powerplant unit having inlet valve means and adapted to operate at a preselected normal speed, the combination of a control member for regulating the inlet valve means, governing means adapted to control the position of the control member to maintain prime mover speed at the preselected normal value, synchronizing means for adjusting the governing means to change the normal position of the control member, first adjustable stop means for establishing a primary limiting position beyond which the governing and synchronizing means cannot cause the control member to move in the valve-opening direction,

25 second adjustable means for establishing a secondary limiting position within the range below said primary limiting position and under-speed release means controlled by the governing means for rendering ineffective the second adjustable means when speed drops below normal to a preselected minimum value whereby the system is restored to control by the governing and synchronizing means as limited by the first adjustable stop means.

30 35 11. In a governing system for a prime mover having motive fluid inlet control means, the combination of a hydraulic motor with a piston for actuating the inlet control means, a source of governor operating fluid under pressure, a first pilot valve for directing motive fluid from said source to the motor, means responsive to prime mover speed for positioning the first pilot valve, a second pilot valve associated with said piston and adapted to interrupt the supply of motive fluid to the first pilot valve when the piston is in a position corresponding to a preselected condition of the inlet control means, and means for positioning the second pilot valve to determine the limiting position to which the first pilot valve can cause said piston to move.

40 45 50 55 60 65 70 75 12. In a governing system for a prime mover having motive fluid inlet control means, the combination of a hydraulic motor with a piston for actuating the inlet control means, a source of governor operating fluid under pressure, a first pilot valve for directing motive fluid from said source to the motor, means responsive to prime mover speed for positioning the first pilot valve, a second pilot valve associated with said piston and adapted to interrupt the supply of motive fluid to the first pilot valve when the piston is in a position corresponding to a preselected condition of the inlet control means, and means for positioning the second pilot valve to determine the limiting position to which the first pilot valve can cause said piston to move, said last-named

positioning means including means for manually moving the second pilot valve to any desired position in its range of movement, and means including an emergency over-speed governor for moving the second pilot valve to a preselected emergency position regardless of the position of said manual means.

13. In a governing system for a prime mover having motive fluid inlet control means, the

17

combination of a hydraulic motor with a piston for actuating the inlet control means, a source of governor operating fluid under pressure, a first pilot valve for directing motive fluid from said source to the motor, means responsive to prime mover speed for positioning the first pilot valve, a second pilot valve associated with said piston and adapted to stop the supply of motive fluid to the first pilot valve when the piston is in a position corresponding to a preselected condition of the inlet control means, and means for positioning the second pilot valve to determine the limiting position to which the first pilot valve can cause said piston to move, said last-named positioning means including means for manually moving the second pilot valve to any desired position in its range of movement, means including an emergency over-speed governor for moving the second pilot valve to a preselected emergency position regardless of the position of said manual means, second means for manually moving the second pilot valve to any position below the upper limit determined by the first-mentioned manual means, and servo-motor means responsive to an operating condition in the powerplant for rendering ineffective said second manual means.

14. In a governing system for a prime mover powerplant unit having motive fluid inlet control means, the combination of a hydraulic motor with a piston for actuating the inlet control means, a source of governor operating fluid under pressure, a first pilot valve for directing motive fluid from said source to the motor, means responsive to prime mover speed for position-

35

18

ing the first pilot valve, a second pilot valve associated with said piston and adapted to interrupt the supply of motive fluid to the first pilot valve when the piston is in a position corresponding to a preselected condition of the inlet control means, and means for positioning the second pilot valve to determine the limiting position to which the first pilot valve can cause said piston to move, said last-named positioning means including means for manually moving the second pilot valve to any desired position in its range of movement, means including an emergency over-speed governor for moving the second pilot valve to a preselected emergency position regardless of the position of said manual means, second means for manually moving the second pilot valve to any position below the upper limit determined by the first-mentioned manual means, servo-motor means for rendering ineffective said second manual means, and means associated with said speed responsive means for actuating the servo-motor when the speed drops below a preselected minimum value.
